UNITED STATES PATENT OFFICE

116,468

DESIGN FOR A PLAQUE OR THE LIKE

Charles C. Meisel, Chicago, Ill.

Application April 12, 1939, Serial No. 84,242

Term of patent 7 years

To all whom it may concern:

Be it known that I, Charles C. Meisel, a citizen of the United States, residing at Chicago, in the county of Cook and State of Illinois, have invented a new, original, and ornamental Design for a Plaque or the like, of which the following is a specification, reference being had to the accompanying drawing, forming part thereof.

I claim:

The ornamental design for a plaque or the like, as shown.

CHARLES C. MEISEL.
